STENCIL PRINTING APPARATUS

John B. Thomas, Watertown, Conn., and Courtney E. Moorhouse, West Englewood, N. J., assignors to Roto-Matic Screen Printer, Ltd., New York, N. Y., a corporation of New York

Original application February 5, 1947, Serial No. 726,504. Divided and this application March 3, 1949, Serial No. 79,412

1 Claim. (Cl. 101—407)

1

This invention relates to an apparatus for printing sheets such as textile fabric webs, plastic films and paper with the aid of a stencil. For simplicity, such apparatus will be referred to hereinafter simply as a "silk screen printing machine," it being understood that said term is merely a trade designation for a stencil printing machine and does not indicate that the stencil necessarily is of silk. It is an object of our invention to provide a silk screen printing machine which will print uniformly, clearly and accurately even when run by an unskilled operator.

It is a more specific object of our invention to provide a silk screen printing machine in which the printing table may be adjusted to provide a desirable printing surface of any vertical profile, even skew, if such a surface is required.

Other objects of our invention will in part be obvious and in part will be pointed out hereinafter.

Our invention accordingly consists in the features of construction, combinations of elements and arrangements of parts which will be exemplified in the construction hereinafter described, and of which the scope of application will be indicated in the appended claims. Certain features of the apparatus shown and/or described, but not claimed herein, are shown, described and claimed in our co-pending application, Serial No. 726,504, filed February 5, 1947, for Stencil Printing Apparatus, of which the present application is a division, and in our co-pending application, Serial No. 79,413, filed March 3, 1949, for Stencil Printing Apparatus.

In the accompanying drawings in which is shown one of the various possible embodiments of our invention,

Fig. 1 is a top plan view of a silk screen printing machine constructed in accordance with our invention;

Fig. 2 is a front view of said machine;

Fig. 3 is an enlarged sectional view taken substantially along the line 3—3 of Fig. 2;

Fig. 4 is an enlarged sectional view taken substantially along the line 4—4 of Fig. 2;

Fig. 5 is a left-hand side view of the printing table with portions partly broken away to show the construction of the table top; and

Fig. 6 is an enlarged sectional view taken substantially along the line 6—6 of Fig. 1.

Referring now in detail to the drawings, 10 denotes a silk screen printing machine embodying our invention and comprising a printing table 12 to either side of which a supply or take-up reel

14, 16 is disposed. The printing table 12 includes a front frame 18 and a rear frame 20 interconnected by tie rods 22. Said table is adapted to be secured to a firm support, such as a floor, and is set by means of levelling screws 24 so that the top of the table is approximately horizontal.

The textile web to be printed is adhesively secured to a blanket 26 of flexible material capable of being rolled and reroled many times without breaking, and yet heavy enough to maintain its own shape when printing pressure is applied thereto. A material which has been found satisfactory for this purpose is heavy commercial linoleum. The blankets are relatively long, for example, seventy-five yards, one end of the blanket being secured by a pressure sensitive adhesive tape to one of the reels and the other end in like manner to the other of the reels. The blanket passes across the table top, being supported there in a manner later described. As the blanket is led from one to the other of the reels its position in a front-to-back sense is held constant so that successive prints will be in front-to-back registration. To this end, we provide narrow guide and spacer belts 28, 30 at the front and back of the blanket adjacent lateral edges thereof.

Conveniently, said belts are secured to the undersurface of the blanket, the attachment being effected in any suitable manner, for instance by means of an adhesive, or by mechanical fastening means such as rivets, or by sewing. Said belts may be made of the same material as the blanket, i. e., linoleum, or any other flexible and relatively strong substance such as rubber alternatively can be employed.

As the blanket passes from one of the reels to the table and from the table to the other of the reels the belts engage two front-to-back registering means whose construction is best seen in Fig. 3. Each said means includes a double flanged guide sheave 32 mounted to rotate about a horizontal axis extending in a front-to-back direction underneath the blanket. Said sheave snugly receives between its flanges the front guide and spacer belt 28. The sheaves are located in proximate relationship to the printing table one to either side thereof as seen in Fig. 2. For this purpose said sheaves either may be journaled in bearings supported from the table or from the reel carrying cradles; the latter type of support being illustrated herein.

It is convenient to associate said sheaves with idling rollers which carry the weight of the belt as it approaches and leaves the table. Accordingly, each sheave 32 is secured to a shaft 34

which also has mounted thereon an idler roller 36. Said idler roller is of reduced diameter at its rear 38 to accommodate the rear guide and spacer belt 30. The idler roller shaft 34 is journaled at its ends in self-aligning flanged cartridge bearings 40 which are secured to a cradle frame 42 for the supply and take-up reels.

Means also is included for holding the blanket down against each idler roller and guide sheave. Such means comprises a pair of keeper wheels 43 rotatably supported on shaft 44 vertically adjustably bolted to angle brackets 45 fastened to the cradle frame. The front keeper wheel 43 captively holds the front guide and spaced belt 28 between the flanges of the guide sheave 32 and the rear keeper wheel holds the back edge of the blanket against the idler roller and prevents the blanket from skewing, when the diameter of the associated reel is so large that the top of the reel is higher than the idler roller.

Printing ink is forced through the stencil S by an elongated scraper blade 46 comprising a rigid backing member or body 47 whose tip 48 is either rigid or resilient depending upon the particular manner in which the machine is used. The scraper blade 46 illustrated herein is entirely rigid, being composed, by way of example, from a thermosetting plastic. The lower portion of the blade is slightly tapered and the tip 48 thereof rounded as best seen in Fig. 6. The ends 30 of said blade are journaled in a pair of blade hangers 50 which are supported on a draw bar 52. The ends of the draw bar are mounted on carriages 54 which ride between rails 56 extending in a front-to-back direction on opposite sides of the table.

The draw bar can be moved back and forth across the stencil screen S either by power, as described in detail in our co-pending application, Serial No. 726,504, or by hand with the aid of a socket 58 mounted on the draw bar and adapted to receive a handle 60.

The stencil screen S constitutes a piece of fabric which has pervious and impervious areas defining a design. The screen has an oblong shape, being elongated in a front-to-back direction. The edges of the screen are secured in a suitable manner, as by gluing, clamping or stapling, to a stencil screen frame 62 of any self-form-maintaining material, such for example as wood. When the scraper is functioning, the stencil screen rests on a textile web 64 carried by the blanket 26. When the scraper is idle and it is desired to shift the blanket in order to bring a fresh portion of the web beneath the screen, the screen is elevated, as described in detail in our co-pending application, Serial No. 726,504. The blanket is shifted either by the hand wheels 66 or by a power drive as explained fully in our said co-pending application.

The opposite ends of the blanket 26 are detachably secured, as with pressure sensitive adhesive tape, to reels 68, 70, one of which may serve as the supply reel and the other as the take-up reel depending upon the direction of blanket travel.

Pursuant to the present invention, as the blanket passes over the printing table it rests upon a substantially flat resilient support such as is afforded by a thick felt pad 72 which in turn is supported on a metal plate 74. Said plate can be vertically adjusted at many points

throughout its area so as to provide the proper type of support for securing a clear and even print over the entire area of the screen. This adjustment is effected by a plurality of tapped sockets 76 held to the underside of the plate 74 by flathead bolts 78 received in countersunk holes in the plate. Each socket fixedly engages, e. g., by welding, a depending threaded rod 80 which freely passes through an opening in the horizontal flange of a channel iron 82 running from the front to the back frame of the printing table. Several such channel irons are provided, the same being spaced from side-to-side of the printing table and each having many threaded rods 80 passing therethrough. The rods are vertically adjusted with respect to the channel irons by nuts 84; that is to say, by turning one of the nuts 84 the associated socket 76 will be raised or lowered and the elevation of the plate at that point correspondingly changed. Lock nuts 86 may be threaded on rods 80 underneath the channel irons.

Similarly adjustable types of supports can be afforded for the guide belts 28, 30. Each of these supports comprise a wooden strip 88 running from side-to-side of the machine directly beneath one of the belts. The strips are supported from the channel irons 82 by collars 90 secured to bolts whose heads are received in countersunk holes in the strips and whose shanks are connected to the channel irons in the same manner as the rods 80.

It will thus be seen that we have provided a machine which achieves the several objects of our invention and is well adapted to meet the conditions of practical use.

As various possible embodiments might be made of the above invention, and as various changes might be made in the embodiments above set forth, it is to be understood that all matter herein described, or shown in the accompanying drawings, is to be interpreted as illustrative and not in a limiting sense.

Having thus described our invention, we claim as new and desire to secure by Letters Patent:

In combination in a silk screen printing machine, a flexible elongated blanket adapted to support a textile web, said blanket having downwardly projecting elements adjacent its lateral edges, a printing table across which the blanket is adapted to move and on which the blanket rests during printing, said table including a flexible metal plate which extends between said elements and is covered with a resilient material, means to independently vary the level of different portion of said plate adjacent and intermediate the edges thereof, members at the back and front of said plate for supporting said elements, and means to independently vary the level of different portions of said members.

JOHN B. THOMAS.

COURTNEY E. MOORHOUSE.
